STAPLE DRIVING MACHINE

Melville Earl Wampler, Chicago, Ill., assignor, by
mesne assignments, to Acme Staple Company,
Camden, N. J., a corporation of New Jersey

Application September 28, 1946, Serial No. 700,099

11 Claims. (Cl. 1—49)

1

The invention relates to staple driving machines generally and more particularly to machines of the spring-driven hammer or tacker type.

One object of the invention is to provide improved hammer driving mechanism for machines of the above general character which is simple in construction and powerful and efficient in operation, and which has few parts subject to wear, all of which parts are readily accessible for replacement.

Another object is to provide a staple driving machine which is compact and light in weight, and which fits conveniently in the hand, thus permitting use for long periods without unduly tiring the operator.

A further object is to provide a staple driving machine adapted to be constructed largely of parts formed by simple stamping or die forming operations, thus substantially reducing manufacturing costs.

Other objects and advantages of the invention will become apparent from the following detailed description of the preferred embodiment illustrated in the accompanying drawings, in which:

Figure 1 is a longitudinal sectional view of a staple driving machine embodying the features of the invention.

Fig. 2 is a side elevational view of the machine with a part of the casing broken away to show the hammer driving mechanism in retracted or cocked position.

Fig. 3 is a fragmentary side view showing the actuating pawl of the driving mechanism substantially at the instant of release.

Fig. 4 is a transverse sectional view taken in a vertical plane substantially on the line 4—4 of Fig. 2.

Fig. 5 is a sectional view taken in a horizontal plane substantially on the line 5—5 of Fig. 1.

Fig. 6 is an exploded view of the casing showing the form and relationship of the component parts.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

For purposes of illustration the improved staple driving machine has been shown in the form of a tacker adapted to drive staples through tags or

2

the like to attach them to boxes or other structures. It will be apparent that the novel features of construction may also be used in stapling machines of the type adapted to drive staples through two or more sheets of material and clinch them on the underside thereof to secure the sheets together.

The machine selected to illustrate the invention comprises generally a hollow rectangular casing 10 having a centrally disposed elongated opening 11 extending through it from side to side to provide for gripping the machine in one hand. The opening 11 is positioned so as to divide the interior of the casing into front and rear compartments 12 and 13 connected by horizontally disposed upper and lower compartments 14 and 15. Extending longitudinally of the casing within the lower compartment 15 is a guideway 16 along which staples 17, herein shown as U-shaped in form, are fed successively to a reciprocating hammer 18 supported and guided in the front compartment 12 of the casing. The hammer is adapted to be retracted manually and to be advanced in its staple driving stroke by spring-actuated mechanism 19 under control of a hand lever 20. The hand lever is pivotally supported on the front end of the casing and disposed so that it may be grasped by the hand gripping the casing.

In accordance with the invention the hammer actuating mechanism 19 is constructed so as to provide ample power for driving the staples 17 into wood or similar material while occupying relatively little space within the casing, so that the latter may be made relatively small and compact. Moreover, the mechanism is constructed so as to reduce the shocks and strains imposed on the hammer, thus materially increasing the useful life of that element.

In its preferred form, the actuating mechanism 19 comprises an elongated plunger 21 disposed within the upper casing compartment 14 and supported and guided for movement longitudinally thereof transversely of the reciprocatory path of the hammer 18. The plunger is supported and guided adjacent its rear end by a heavy cross member 22 rigidly secured to the side walls of the casing, the member being apertured to slidably receive the rear end portion of the plunger which is preferably cylindrical and of reduced diameter as compared with the forward end portion thereof. The plunger is urged forwardly by suitable spring means, herein shown as a coiled compression spring 23 encircling the cylindrical end of the plunger and bearing at opposite ends

against the cross member 22 and a rearwardly facing shoulder 24 formed on the plunger. Forward movement of the plunger is limited by an abutment member or head 25 engaging with the cross member 22. As herein shown, the head 25 comprises a nut threaded on the end of the plunger. A resilient member or bumper 26 may be interposed between the head and the cross member to absorb the shock incident to the interruption of the forward movement of the plunger.

At its forward end the plunger 21 is operatively connected with the hammer 18 by a toggle linkage which acts to transfer the power of spring 23 to the hammer with a high degree of efficiency and with a substantially complete absence of shock. As herein shown, the hammer 18 comprises an elongated relatively thin staple-engaging tongue 30 secured to the front face of and projecting downwardly from a vertically slotted guiding head 31. The toggle linkage comprises upper and lower links 32 and 33 connected by a pivot pin 34. The upper link is pivotally secured to the casing structure by a bolt 35 which additionally serves as a pivot for the hand lever 20. The link 33 extends into the slot in the hammer head 31 and is pivotally connected thereto by a pin 36. An arm 37 rigid with the link 33 and projecting rearwardly from the upper end thereof is received in a slot in the forward end of the plunger 21 and is secured thereto by a pivot pin 38.

In the normal or idle condition of the machine the hammer 18 is yieldably urged to the advanced position shown in Fig. 1, in which the tongue 30 of the hammer is projected substantially flush with the lower surface of the casing 10. As the plunger is retracted, the spring 23 is compressed and the hammer is shifted upwardly to withdraw the tongue 30 above the staple guideway 16 to permit the feeding of a staple into position to be driven by the downward movement of the tongue. The compression of the spring 23 thus prepares the hammer for delivery of a driving blow which is initiated by release of the plunger to the action of the spring.

Means are provided for retracting the hammer 18 and for releasing it to the action of the compressed spring 23 by simply rocking the hand lever 20 down against the casing 10. The hand lever, herein shown as a generally channel shaped sheet metal stamping adapted to fit over the casing, is pivotally supported at the front end of the casing, in this instance by the pin 35 extending through the upper toggle link 32. The rear portion of the lever extends over the top of the casing so that it may be readily grasped in the palm of the hand with the fingers gripping the casing through the opening 11. Thus, a simple squeezing action provides the force required to compress the spring 23 and to retract the hammer 18.

To provide an operative connection between the hand lever 20 and plunger 21, the lever carries a dog or pawl 40 adapted when the lever is depressed to engage an upright forwardly facing shoulder 41 on the plunger 21 to shift the plunger rearwardly. The cooperating parts of the pawl and plunger are shaped so that the pawl is automatically disengaged from the shoulder 41 when the plunger reaches its fully retracted position. Upon such release the plunger is advanced by the spring 23 to drive the hammer downwardly, as above explained.

In the exemplary machine the pawl 40 com-

prises a generally rectangular member of steel or other suitable material, pivotally supported between the side flange of the lever 20 by a pin 42, the latter being located so that the pivotal axis of the pawl is disposed forwardly of the shoulder. One corner of the member is cut away or rounded off, as indicated at 43, to provide clearance so that the pawl may rock between the position shown in Figs. 1 and 2, a torsion spring 44 yieldably urges the pawl to the upright position shown in Fig. 1, whereby its lower corner portion is positioned for operative engagement with the shoulder 41 of the plunger.

To provide for automatic disengagement of the pawl from the shoulder 41, the plunger is formed with a cam surface 45 sloping upwardly from the base of the shoulder. The arrangement is such that as the plunger approaches its limit position the cam surface engages the forward edge of the pawl, as shown in Fig. 3, and rocks the lever upwardly out of engagement with the shoulder. The shoulder engaging portion of the pawl may be rounded or otherwise appropriately shaped, as indicated at 46, to facilitate the release of the plunger. Accordingly, the driving of a staple may be effected by merely rocking the hand lever 20 from its normal rest position shown in Fig. 1 to a position closely overlying the top of the casing, as shown in Fig. 2, such movement serving to compress the spring 23 and thereby store up energy for advancing the hammer 18 in its staple driving stroke and to release the spring, and initiate the driving action. The hammer 18 of course is retracted in the downward movement of the hand lever to permit the feeding of a staple into position to be driven by the hammer.

The novel construction and relationship of the hammer 18 and its driving mechanism, and particularly the mounting of the spring actuated plunger 21 for movement transversely of the path of the hammer, produces a very compact and conveniently shaped instrument. Moreover, this novel arrangement of parts permits the casing 10 to be constructed of simple and inexpensive parts conveniently produced by die forming or stamping operations. In the exemplary embodiment, the casing 10 comprises a pair of generally rectangular side plates 50 and 51 having inturned flanges 52 (Fig. 5) at one edge coacting to form the front wall of the casing. Inturned flanges 54 and 55 (Fig. 6) formed on the rear and top edges of the side plates and flanges 56 encircling the hand openings 11 in the plates cooperate with the flanges 52 to hold the side plates in proper spaced relation when assembled. The flanges 56 additionally provide a smooth surface for gripping in the hand.

The bottom of the casing 10, in this instance, is formed by an elongated member or bottom strip 60 adapted to fit between the side plates 50 and 51 and having at its rear end a pair of laterally spaced upstanding ears 61. The ears 61 are spaced apart so as to straddle the side plates 50 and 51 and assist in holding them in assembled relation.

At its forward end the bottom strip 60 is provided with a pair of laterally spaced bent-up lugs 62 adapted to fit within a rearwardly facing generally U-shaped member 63 which serves as a front plate for the lower portion of the casing. The latter is cut away or notched to receive the front member and the lugs 62, which are positioned to lie substantially flush with the side plates. The legs of the front member extend rearwardly and are spaced apart so as to straddle

the side plates 50 and 51 and assist further in holding the plates in assembled relation. A suitable bolt or screw 64 (Figs. 1, 2 and 5) extends through the legs of the front plate and through the side plates for securing the parts together. The front member 63 and bottom member 68 are formed with cooperating means for holding the latter in place. As herein shown, the cooperating means comprises tabs 65 (Fig. 6) projecting forwardly from the lugs 62 and engaging in notches 66 in the front member. At the rear end of the casing the parts are secured together by a pin 67.

The staple guide 16 previously referred to includes a channel-shaped member 68 secured to the bottom plate 60 in upwardly faced relation and extending longitudinally of the same. The member 68 preferably terminates a short distance rearwardly of the front member 63 to provide an opening for the passage of staples and the staple driving tongue 30 of the hammer. Guide strips 69 rigidly secured to the side plates 50 and 51 extend generally parallel to the guide member 68 and project inwardly to overlie the ends of the staples carried on the member to maintain the staples on the guide in all positions of the machine. As shown in Figs. 1 and 2, the guide strips are notched similar to the side plates 50 and 51 and the staple retaining function is performed by auxiliary guide elements 70 carried by the upstanding lugs 62 of the bottom plate.

As will be seen by reference to Figs. 1 and 2 of the drawings, the strips 69 are extended upwardly at 71 adjacent to the front end of the casing to serve as guides for the reciprocatory hammer head 31. The front edges of the extensions 71 are spaced rearwardly from the flanges 52 of the side plates and thus form guide channels 72 for slidably receiving the marginal edge portions of the tongue 30, whereby the hammer 18 is guided for reciprocation.

The feeding mechanism for advancing the staples on the guides 16 may be of conventional type, and as herein shown, comprises a channel-shaped shoe 73 adapted to straddle the channel member 68. The shoe is slidably mounted on an elongated rod 74 by means of spaced depending lugs 75 struck from the upper wall of the shoe and apertured to receive the rod. A spring 76 interposed between a laterally projecting arm 77 at the rear end of the rod and shoe urges the latter forwardly, thus tending to push the staple 17 into position to be driven by the hammer 18. The feed mechanism is retained in place in the casing by the arm 77, which is formed with a hook-like end adapted to engage a pin 78 within the casing. The latter is open at its rear end so that the hook may be disengaged and the entire mechanism withdrawn for loading staples on the guide channel. A head 79 on the forward end of the rod 74 prevents the shoe from being pushed off when the mechanism is withdrawn from the casing.

It will be apparent from the foregoing that the invention provides a stapling machine of novel and advantageous construction. The driving mechanism is very simple and compact, yet powerful and efficient in operation. Shocks and strains imposed on the operating elements of the machine are reduced to a minimum, and the parts subject to wear are readily accessible for replacement. The machine is light in weight and conveniently fits the hands of the operator

so that it may be used for long periods without causing undue fatigue.

I claim as my invention:

1. A staple driving machine having, in combination, a reciprocating staple driving hammer, feed mechanism for presenting a succession of staples to said hammer when the latter is retracted, means for reciprocating said hammer including a plunger supported for movement transversely of the path of the hammer, a linkage connecting said plunger with said hammer, spring means acting on said plunger and urging the plunger and said hammer to an advanced position, manually operable means for retracting the plunger and said hammer against the force of said spring means, and means operative automatically upon predetermined retraction of said plunger for releasing said manually operable means therefrom, said spring means acting upon such release to advance said hammer to drive the staple presented thereto.

2. In a staple driving machine, in combination, a casing, a reciprocable hammer supported and guided at one end of the casing, a plunger supported in the casing for movement transversely of said hammer, a toggle linkage connecting said plunger and said hammer, spring means acting on said plunger tending to advance said plunger, a hand lever pivoted on said casing, a pawl carried by said hand lever engageable with said plunger upon actuation of the lever to retract the plunger and said hammer against the force exerted by said spring means, said plunger being shaped to disengage said pawl upon a predetermined retraction whereby to free the plunger and said hammer to the action of said spring means.

3. In a staple driving machine, in combination, a casing, a reciprocating hammer in said casing, means for reciprocating said hammer including a plunger slidably supported in said casing, a linkage connecting said plunger and said hammer, spring means urging said plunger and said hammer to an advanced position, a hand lever pivoted on said casing, a pawl pivotally secured to said lever and having its free end engageable against a shoulder formed on said plunger whereby to retract the plunger upon depression of said lever, said plunger having a cam surface disposed forwardly of said shoulder operative to raise the free end of said pawl out of engagement with said shoulder upon further depression of said lever, said spring means acting upon such disengagement of the pawl to advance said plunger and said hammer.

4. A staple driving machine having, in combination, a hollow generally rectangular casing having an elongated opening extending through opposite sides and dividing the interior thereof into a front compartment opening into vertically spaced rearwardly extending upper and lower compartments, a reciprocating hammer mounted in the front compartment, staple feeding mechanism mounted in the lower compartment, a hammer actuating plunger mounted in the upper compartment, a hand lever pivoted on said casing adjacent the upper end of the front compartment and extending rearwardly along the top of the casing, and means providing an operative connection between said lever and said plunger, the portion of said casing defining said upper chamber serving as a hand grip for operating said lever.

5. In a staple driving machine, in combination, a reciprocating hammer, means for recipro-

cating said hammer including a plunger slidably supported for movement transversely of the path of said hammer, a linkage connecting said plunger with said hammer, spring means acting on said plunger to urge the hammer to an advanced position, a notch in said plunger presenting a gradually sloping surface terminating in an abrupt forwardly facing shoulder, a lever supported to swing toward and from said plunger, a pawl pivotally supported at one end on said lever, the pivotal axis of said pawl being located forwardly of said notch whereby the free end of the pawl is adapted to engage said shoulder and retract said plunger in response to the depression of said lever, said pawl being rocked about its pivot in the depression of said lever until the free end thereof is disengaged from said shoulder and the plunger thereby released to the action of said spring means.

6. In a stapling machine, in combination, a hollow sheet metal casing, a reciprocating hammer supported and guided at one end of said casing, hammer reciprocating means including an elongated plunger having one end operatively connected by a toggle mechanism with said hammer, a cross member in said casing apertured to slidably receive the other end of said plunger, a spring interposed between said cross member and a shoulder on said plunger yieldably urging the same in a direction to advance said hammer, and abutment means on said other end of the plunger engageable with said cross member to define the limit position of the plunger and said hammer.

7. In a staple driving machine, in combination, a hammer supported and guided for reciprocation, hammer actuating mechanism including a plunger supported and guided for reciprocation transversely of the reciprocatory path of the plunger, spring means yieldably urging said plunger toward an advanced position, means for retracting said plunger against the force exerted by said spring and for releasing the plunger to the action of the spring, and means interposed between said plunger and said hammer operative to transmit the movements of the plunger to the hammer.

8. In a staple driving machine, in combination, a hammer supported and guided for reciprocation, hammer actuating mechanism including a plunger supported and guided for reciprocation transversely of the reciprocatory path of the hammer, spring means yieldably urging said plunger toward an advanced position, means for retracting said plunger against the force exerted by said spring and for releasing the plunger to the action of the spring, and a toggle linkage operative to transmit the movements of said plunger to said hammer.

9. In a stapling machine, in combination, a staple driving hammer, mechanism for actuating said hammer, feed mechanism for supplying a succession of staples to said hammer, a casing

5 enclosing said hammer and said mechanisms including a pair of complementary side members, a bottom member adapted to fit between said side members, a pair of upstanding ears at one end of said bottom member adapted to straddle said side members adjacent the rear end of the casing for holding the members in assembled relation, and a generally U-shaped front member adapted to fit over the front end of the casing to hold the side members in assembled relation.

10 10. In a stapling machine having a staple driving hammer, hammer actuating mechanism and staple feeding mechanism, the combination 15 of a casing for enclosing said hammer and said mechanisms comprising a pair of complementary side members assembled to face-to-face relation, a front member secured to said side members and adapted to hold them in assembled relation, a bottom member having means forming a guideway for staples to be acted on by said feeding mechanism, and means securing said bottom member to said casing for convenient detachment to permit removal of jammed staples, said securing means including elements at one end of said bottom member coacting with said front member, and other elements adjacent the opposite end of said bottom member adapted to extend over said side members and to be secured thereto.

11 30. In a stapling machine having a staple driving hammer, hammer actuating mechanism and staple feeding mechanism, the combination 35 of a casing for enclosing said hammer and said mechanism comprising a pair of complementary side members assembled in face-to-face relation, a front member secured to said side members and adapted to hold them in assembled relation, a bottom member having means forming 40 a guideway for staples to be acted on by said feeding mechanism, and means securing said bottom member to said casing for convenient detachment to permit removal of jammed staples, said securing means including tabs projecting 45 from the front end of said bottom member and engaging in notches in said front member, and upstanding ears adjacent the rear end of said bottom member extending over and secured to said side members.

50 MELVILLE EARL WAMPLER.
